UNITED STATES PATENT OFFICE.

MEADE WILDRICK, OF SAVANNAH, GEORGIA.

KEYLESS LOCK.

1,373,283.

Specification of Letters Patent. Patented Mar. 29, 1921.

Application filed June 2, 1920. Serial No. 385,926.

To all whom it may concern:

Be it known that I, MEADE WILDRICK, a citizen of the United States, residing at Savannah, in the county of Chatham and

5 State of Georgia, have invented certain new and useful Improvements in Keyless Locks; and I do hereby declare the following to be a full, clear, and exact description of the invention, such as will enable others skilled 10 in the art to which it appertains to make and use the same.

My present invention relates to improvements in keyless locks, and it is intended to provide a mechanism which may be used in 15 combination with locks of standard construction, or of special design, in which the necessity for a key is done away with.

According to my invention I provide a combination wheel arrangement in connection with a locking bolt and other details, whereby the lock may be set at any given 20 combination and can be operated only by a person knowing said combination and understanding the mode of operation of the 25 lock.

My invention is similar in certain respects to the well known combination locks used on safes, vaults, or the like.

A lock designed according to my invention 30 is applicable to a great variety of uses, and may be made wholly mechanical, or part mechanical and part electrical, to be hereinafter more fully described.

In the accompanying drawings I show the 35 lock as applied to various purposes, these being merely typical, but it is not intended to limit the use of the lock to the particular purposes illustrated in the drawings or described in the specification.

40 The invention will be more fully understood after reference to the accompanying drawings, in which like parts are indicated by similar reference symbols throughout the several views, and in which:—

45 Figure 1 shows a front elevation of a lock for a trunk, suitcase, chest, or the like, the lock being in the closed position and parts being broken away.

Fig. 2 shows a section along the line 2—2 50 of Fig. 1, parts being shown in elevation, the

lock being shown closed in full lines and open in dotted lines.

Fig. 3 is a perspective view of the locking bolt, with the parts carried thereby.

Fig. 4 is a side elevation of one of the 55 combination wheels, parts being broken away.

Fig. 5 is a side elevation of the wheel shown in Fig. 4 as seen from the left of said figure.

Figs. 6 to 10 show the lock as applied to the door of a house, safe, or the like;

Fig. 6 being a front elevation of the lock, parts being broken away.

Fig. 7 shows a section along the broken 65 line 7—8 of Fig. 6, and looking in the direction of the arrows, but with the lock in the open or unlocked position.

Fig. 8 is a similar view to Fig. 7, but shows the lock in the closed or locked position.

Fig. 9 shows a section along the line 9—9 of Fig. 6, and looking in the direction of the arrows.

Fig. 10 shows a section along the line 75 10—10 of Fig. 7, and looking in the direction of the arrows.

Figs. 11 to 13 show the lock as applied to a padlock;

Fig. 11 shows a front view of the padlock 80 with the hasp shown in full lines, in the closed or locked position, and in dotted lines in the open or unlocked position, and parts of the lock being shown as broken away.

Fig. 12 shows a section along the line 85 12—12 of Fig. 11, and looking in the direction of the arrows.

Fig. 13 shows a section along the line 13—13 of Fig. 11, and looking down.

Figs. 14 to 17 show the lock as used for 90 locking electric switches to prevent the unauthorized throwing of the switches for completing the electric circuit as desired on automobiles, motor boats, or the like;

Fig. 14 being a front view of the casing 95 in which the switches and the lock are mounted.

Fig. 15 shows a section along the line 15—15 of Fig. 14, and looking in the direction of the arrows.

85

100

Fig. 16 shows a section along the line 16—16 of Fig. 14, and looking in the direction of the arrows; and

Fig. 17 is a rear view of the interior of 5 the casing, the rear cover being removed.

Referring first to Figs. 1 to 5, which show 10 the keyless lock as applied to a trunk, chest, dress suitcase, or the like, A represent the lock casing which is fastened to the receptacle X in any convenient way, as by means 15 of the rivets C. This casing preferably comprises the plate a with the housing a' secured thereto as by means of the bolts a''. This housing comprises two chambers, one, 20 the larger chamber, A' for the locking bolt and combination wheels, and the smaller chamber A'' for the locking plate carried by the hasp. The housing is transversely slotted, as at a³, to permit the insertion of the 25 said locking plate, and as at a⁴ to disclose the outer numbers of the combination wheels.

B represents the hasp which is hinged as 30 at b to the plate D carried by the plate D', which plates D and D' are secured to the receptacle X in any convenient way, as by means of the rivets C'. The hasp is shown in the closed and locked position in full lines in Fig. 2, and in the open position, in dotted lines in said figure, and it is also 35 shown in the closed and locked position in dotted lines in Fig. 1.

The means for locking the hasp comprise 40 the locking plate E, preferably slotted at each end, as at e⁰, and provided with a boss e adapted to project into a socket b⁰ in the hasp. The plate E is connected by means 45 of the stem E' to the handle E'' which has an annular bottom e². This stem E' is rigidly secured to the locking plate E in any 50 convenient way, as by means of the nut e', and the connection is such that when the handle E'' is turned the locking plate E will also be turned.

F represents the locking bolt which has 55 attached thereto any convenient handle, such as the knurled head f. This locking bolt is provided with three axial ribs f', f² and f³, and with a downwardly projecting locking bar F' which includes the vertical 60 legs f⁴ and f⁵, with a slot between them, and the cross piece f⁶ at the bottom. These ribs f', f² and f³ slide in grooves g', g² and g³ in the frame of the bearing block G mounted 65 in the lock casing. The rear face of this frame is cut away, as at g, to permit movement of the locking bar F', as shown in Fig. 2.

Revolutely mounted on the shaft I in the lock casing are a plurality of combination 70 wheels, of which I have shown three, H, H' and H'', but there may be two or more of these combination wheels if desired. I prefer to use three as affording sufficient protection for all practical purposes without 75 unnecessarily complicating the mechanism,

but two may be used if desired. These combination wheels are all preferably of similar construction, one of which is shown in detail in Figs. 4 and 5, in which the body of the wheel is provided with a segmental slot h⁰ just inside the radial slot h. The periphery of the wheel is preferably grooved, as at h', and provided with screwthreaded sockets h². The segmental strips K are mounted in these grooves, bearing numbers 80 one to nine, as shown in Fig. 5, and these strips are secured in place by clamp screws L engaging in the corresponding sockets h².

In order to vary the combination, it will 85 be sufficient to move the said screw L and shift the segmental strips K around through a distance sufficient to change the reading of the exposed figures when the slot h registers with the cross piece f⁶ of the locking bar F'. A few only of these numbers on each wheel 90 will be exposed in the openings a⁴ of the lock casing as indicated in Fig. 1. It will be noted that when the three wheels H, H' and H'' are turned with their radial slots h registering with the cross piece f⁶, the locking bolt F may be drawn to the front, as indicated in dotted lines in Fig. 2, but if any one of these wheels is turned so that its slot h does not register with the cross piece f⁶, then it will be impracticable to pull 95 the locking bolt to the front. It will also be obvious that it would be very difficult, in fact impossible, for all practical purposes for anyone not familiar with the combination to set the three combination wheels so 100 that all three slots h will simultaneously register with the cross piece f⁶ of the locking bar F'.

Assuming the parts to be in the position 105 shown in full lines in Fig. 2, in order to release the hasp it will be necessary to see that all three of the wheels have their slots h registering with the cross piece f⁶. The bolt being in the position shown in full lines, its rib f' will engage in one of the notches 110 e⁰ of the locking plate E carried by the hasp. Now if the bolt be pulled forward to the position shown in dotted lines in Fig. 2, the cross piece f⁶ will pass through the slots h in the rings, and the rib f' will move 115 clear of the notch e⁰ permitting the locking plate E to be turned by means of the handle E''.

When this locking plate E is turned 120 through a right angle from the position shown in Figs. 1 and 2, it will register with the transverse slot a³ in the lock casing, and the hasp may be swung clear to the position shown in dotted lines in Fig. 2, and the receptacle X will be unlocked and the lid may 125 be lifted in the usual way.

In the modification shown in Figs. 6 to 10, I show a similar keyless lock arrangement attached to a door knob, with means whereby the door may be freely opened from the 130

inside at any time, but can be opened from the outside only when the combination wheels are set at the proper position for permitting the sliding of the locking bolt, as 5 already described in connection with Figs. 1 to 5.

In the modification shown in Figs. 6 to 10, M represents a suitable metal casing mounted in the door X' in any convenient 10 way, which casing preferably comprises a housing M' and a cover or rear plate M² secured to said housing in any convenient way, as by means of the screw bolts m. The locking bolt F is similar to that already described 15 with reference to Figs. 1 to 5, except that it may be more convenient for purposes of assembly to fasten the knurled head f to the main body of the locking bolt by means of a stem F⁰ and nut f⁰.

20 In this modification the combination wheels H, H' and H² are constructed and coact with the locking bolt precisely as already described with reference to Figs. 1 to 5. Slight changes are made, however, 25 in the device controlled by the combination lock already described, and which will now be pointed out.

N' represents the front knob of a door, carried by the stem N, the rear end of said 30 stem preferably being provided with a flange or set collar n to which the stub shaft N² is connected, which stub shaft carries a downwardly projecting plate or rib N³, slotted as at n³ to register with the upper 35 rib f' on the locking bolt F when said locking bolt is pulled forward, as shown in Fig. 8.

In Fig. 7 the locking bolt is shown in the position for releasing the front door 40 knob, but in Fig. 8 it is shown in the position for locking the same. Where it is desired to open or close the door from one side only, as with safes, vault doors, or the like, a single knob with stem would suffice, 45 as just described; but in order that the door may be freely opened from within some suitable arrangement should be provided for shooting the ordinary bolt O used in holding the door closed. Such an arrangement is 50 shown in detail in Figs. 6 and 7, in which the bolt O is chambered, as at o, to receive the coil spring O' normally tending to push the said bolt outward to the position for holding the door closed. The spring O' 55 mounted in the bolt may bear against the guide lug O² attached to the lock casing, as at o², and the outward travel of the said bolt O may be limited by the shoulder o', see Fig. 6.

60 The lower side of the bolt O is provided with rack teeth o³, meshing with the segmental teeth p on the housing P, carried by the stem P' to which the inside door knob P² is rigidly attached. This housing is chambered as at p⁰ to receive the end of the stub

shaft N² which carries the spring-pressed pawl Q engaging with the ratchet teeth p' on the inner wall of the chamber p⁰, as shown most clearly in Fig. 10. By this arrangement the knob P² may be used to slide the 70 bolt O in either direction, irrespective of whether the combination lock is on or not.

In order to operate or open the door from the front, it will be necessary to have the slots h in the various combination wheels so 75 set that the cross piece f⁰ may be slipped from the position shown in Fig. 8 to that shown in Fig. 7. When the parts are in the position shown in Fig. 7, the door may be opened with equal facility from either the 80 front or the rear; but if the bolt F be in the position shown in Fig. 8, and any one of the combination wheels be turned so that its slot h does not register with the travel 85 of the cross piece f⁰, then it will be impracticable to open the door from the front.

In the arrangement shown in Figs. 11 to 13, I have shown my invention as applied to use with a padlock. In this modification the combination wheels are similar in construction and operation to those already described, and coact in the same way with the locking bolt F. The only difference in the construction of the said locking bolt being that the side ribs f² and f³ are made somewhat deeper as shown in Fig. 11, and the top rib indicated at f' in the preceding views is omitted as unnecessary.

In this modification the locking bolt is shown as built up of a stem F⁰, carrying 100 the knob or handle f and the sleeve F², carrying the side ribs f² and f³, and the locking bar F', similar to the locking bar already described. This sleeve F² is secured to the stem F⁰ by means of a set screw f' 105 which may be inserted through the opening s¹ in the housing block S, which block is inserted in the casing R. The casing R, may be provided with an internally projecting rib r, and the block S may be secured thereto by means of a screw r', see Fig. 11. Thus the casing R and the housing block S effectually mask all of the parts, except the shackle T and the exposed portions of the combination wheels which project into the slots r⁰ provided in the front of the casing R.

The housing block S is provided with a chamber s to receive the arm t of the shackle T, which arm is preferably provided with 120 a flange t' to prevent it from being withdrawn from the casing R, as shown in Fig. 11. The shackle is U-shaped in cross section, and the two legs are provided on opposite sides with the notches t² and t³ to 125 engage the ribs f² and f³ of the locking bolt, when the shackle is in the closed and locked position, as shown in Figs. 11 and 12.

It will be obvious that unless the combination wheels are so set that their slots h 130

will all register with the cross piece f^6 , then the bolt F cannot be pulled forward and the shackle will be held in the locked position. When the combination wheels are 5 so set that its slots h all register with the cross piece f^6 , then the locking bar F' may be pulled forward, causing the ribs f^2 and f^3 on the locking bolt to release the shackle and permit it to be drawn to the position 10 shown in dotted lines in Fig. 11, and then rotated about its leg t if desired.

In the modification shown in Figs. 14 to 15, I have shown my invention as applied to locking the various electric circuits of an automobile. U represents the casing, preferably flanged at its front, as at u , and secured to the instrument board, not shown, of the automobile. This casing is chambered, as at U^0 , and the rear end is closed 20 by an insulating disk U' carrying the binding posts V and V' connected by suitable conductors to the source of electricity carried by the vehicle, not shown.

These binding posts are shown in Fig. 25 16, and one of them only is shown in Fig. 15.

Mounted in this casing is an insulating bearing block U^2 in which the locking bolt F^3 is slidably mounted. This locking bolt 30 carries two side ribs f^2 and f^3 adapted to engage in the teeth w^2 and w^3 on the segments carried by the shafts w and w' , on which shafts are fastened the switch arms W and W' , respectively, which make contact with the contact points for operating 35 the various devices carried by the car.

I have shown in Fig. 17 the two switches W and W' in the off position. By turning the switch W' to make contact with the 40 point y the circuit is closed through the binding post Y, which may control, for instance, the circuit for the side and rear lights. The binding post Y' carries the contact point y' which may control the auxiliary 45 head and the rear lights; and the binding post Y^2 may carry the contact point y^2 for controlling the head and rear lights.

The switch W may be used to control the circuits through the binding posts Y^3 50 and the contact y^3 from the battery when the magneto is not in operation, and through the binding posts Y^4 and the contact point y^4 when the magneto is on.

The cross piece f^6 carries, insulated therefrom, the contact strip Z, see Figs. 16 and 55 17, which makes contact from the main binding posts V and V' and closes and breaks the circuit according to whether the locking bolt is in the rear position shown 60 in full lines in Fig. 15, or is moved more or less forward to break the circuit.

The switches W and W' are preferably provided with thumb lugs or handles W^0 for convenience in operating the same.

65 It will be obvious that the bolt F^3 can-

not be moved forward unless the radial slots h of all the combination wheels register with the cross piece f^6 , and that if any one of these wheels be turned so that its slot will not register with said cross piece 70 the locking bolt F^3 cannot be moved axially.

In the operative position, the locking bolt F^3 is shoved inward, as shown in Fig. 15, and when in the locked position the said locking bolt is drawn outward until the ends 75 of the ribs f^2 and f^3 engage the rear wall of the front face of the casing, at which time the cross piece f^6 will have been drawn into the segmental slot h^0 in all three of the combination wheels.

Now if any one of the combination wheels be turned through an angle, the locking bolt will be held in the withdrawn position, and all of the electric circuits will be broken.

The above described contact strip Z may 85 be made independent of the contacts Y' , Y^2 , Y^3 and Y^4 if desired.

It will be noted that in all of the constructions hereinbefore described the set screws L project somewhat and will prevent 90 the combination wheels from being turned far enough to expose the slots h through the corresponding recesses in the front of the lock casing, otherwise it might be possible for an expert to turn these wheels, note 95 the position of the slots, then turn them back through 180° and thus quickly ascertain the combination.

If it be desired the various combination wheels may have the numbers thereon shown 100 in luminous paint so that the combination may be set at night without the use of artificial light.

While I have illustrated the various combination wheels provided with indicia in the 105 form of Roman numerals, it will be obvious that the letters of any language may be substituted for the Roman numerals, or, if preferred, designs or hieroglyphs may be used on the various combination wheels, and 110 these indicia may be varied from time to time by simply shifting the adjustable strips on the periphery of any one or more of the various combination wheels.

It will be noted that all of the various 115 devices hereinbefore described possess the following elements in common:

(1) A sliding locking bolt carrying ribs which serve to lock one or more parts against being improperly opened or controlled; and that this sliding bolt carries a locking bar having a transverse cross piece.

(2) A series of combination wheels, each provided with a segmental slot opening into a radial slot, and that unless all of the 125 wheels are set with the radial slot registering with the cross piece, it will be impossible to operate the device.

(3) There is a third device locked or released by the sliding locking bolt, and the 130

movement of the locking bolt is controlled by the position of the combination wheels aforesaid.

While I have shown the invention as applied to the various purposes hereinbefore described, it will be obvious that it may be used in a great many other relations which are not herein described; and I do not mean to limit the invention to any specific use.

10 It will also be obvious that various modifications might be made in the construction, combination and arrangement of parts which could be used without departing from the spirit of my invention; and I do not mean 15 to limit the invention to such details except as particularly pointed out in the claims.

Having thus described my invention what I claim and desire to secure by Letters Patent of the United States is:—

20 1. In a combination lock, the combination with a casing, and a shaft mounted in said casing, of a plurality of combination wheels revolvably mounted on said shaft, each wheel being provided with a segmental slot, and 25 with a radial slot opening outward from said segmental slot, with indices carried on the periphery of each wheel away from its radial slot, a locking bolt slidably mounted in said casing and carrying a cross piece 30 adapted to simultaneously pass through all of said radial slots when all of said wheels are set at a predetermined combination, the said locking bolt being also provided with axial ribs thereon, and a movable member 35 controlling the device to be locked provided with a notch adapted to engage one of said ribs on said bolt when the said bolt is moved to the locking position but to clear said rib when said bolt is moved to the unlocking 40 position.

2. In a combination lock, the combination with a casing and a shaft mounted in said casing, of a plurality of combination wheels revolvably mounted on said shaft, each wheel being provided with a segmental slot, and 45 with a radial slot opening outward from said segmental slot, a segmental strip, with indices provided thereon, adjustably connected to the exterior of each wheel away 50 from its radial slot, a locking bolt slidably mounted in said casing and carrying a cross piece adapted to simultaneously pass through all of said radial slots when all of said wheels are set at a predetermined combination, the said locking bolt being also provided with axial ribs thereon, and a movable member 55 controlling the device to be locked provided with a notch adapted to engage one of said ribs on said bolt when the said bolt is moved to the locking position, but to clear said rib when said bolt is moved to the unlocking 60 position.

3. In a combination lock, the combination with a casing, and a shaft mounted in said 65 casing, of a plurality of combination wheels

revolvably mounted on said shaft, each wheel being provided with a segmental slot, and with a radial slot opening outward from said segmental slot, a circumferential groove in the periphery of each wheel with a plurality of radial sockets projecting inward from said groove, a segmental strip, with indices provided thereon, mounted in said groove, pins projecting through said strip into said sockets for adjustably mounting 70 each strip on its corresponding wheel, a locking bolt slidably mounted in said casing and carrying a cross piece adapted to simultaneously pass through all of said radial slots when all of said wheels are set at a 80 predetermined combination, the said locking bolt being also provided with axial ribs thereon, and a movable member controlling the device to be locked provided with a notch adapted to engage one of said ribs 85 on said bolt when the said bolt is moved to the locking position, but to clear said rib when said bolt is moved to the unlocking position.

4. In a combination lock, the combination 90 with a casing provided with a slotted face plate, and a shaft mounted in said casing in rear of said slots, of a plurality of combination wheels revolvably mounted on said shaft and projecting into said slots, each 95 wheel being provided with a segmental slot, and with a radial slot opening outward from said segmental slot, with indices carried on the periphery of each wheel away from its radial slot, a locking bolt slidably mounted in said casing and having transversely disposed legs carrying a cross piece, 100 said cross piece being adapted to simultaneously pass through all of said radial slots when all of said wheels are set at a pre- 105 determined combination, the said locking bolt being also provided with axial ribs thereon, and a movable member controlling the device to be locked provided with a notch adapted to engage one of said ribs 110 on said bolt when the said bolt is moved to the locking position but to clear said rib when said bolt is moved to the unlocking position.

5. In a combination lock, the combination 115 with a casing provided with a slotted face plate and a shaft mounted in said casing in rear of said slots, of a plurality of combination wheels revolvably mounted on said shaft and projecting into said slots, each 120 wheel being provided with a segmental slot, and with a radial slot opening outward from said segmental slot, a segmental strip, with indices provided thereon, adjustably connected to the exterior of each wheel away 125 from its radial slot, a locking bolt slidably mounted in said casing and having transversely disposed legs carrying a cross piece, said cross piece being adapted to simultaneously pass through all of said radial slots 130.

when all of said wheels are set at a pre-determined combination, the said locking bolt being also provided with axial ribs thereon, and a movable member controlling the device to be locked provided with a notch adapted to engage one of said ribs on said bolt when the said bolt is moved to the locking position, but to clear said rib when said bolt is moved to the unlocking position.

10 6. In a combination lock, the combination with a casing provided with a slotted face plate, and a shaft mounted in said casing in rear of said slots, of a plurality of combination wheels revolubly mounted on said 15 shaft and projecting into said slots, each wheel being provided with a segmental slot, and with a radial slot opening outward from said segmental slot, a circumferential groove in the periphery of each wheel with a plurality of radial sockets projecting inward

from said groove, a segmental strip, with indices provided theron, mounted in said groove, pins projecting through said strip into said sockets for adjustably mounting each strip on its corresponding wheel, a 25 locking bolt slidably mounted in said casing and having transversely disposed legs carrying a cross piece, said cross piece being adapted to simultaneously pass through all of said radial slots when all of said wheels 30 are set at a predetermined combination, the said locking bolt being also provided with axial ribs thereon, and a movable member controlling the device to be locked provided with a notch adapted to engage one of said 35 ribs on said bolt when the said bolt is moved to the locking position, but to clear said rib when said bolt is moved to the unlocking position.

MEADE WILDRICK.
